Patented Oct. 13, 1936

2,057,451

UNITED STATES PATENT OFFICE

2,057,451

PHOTOGRAPHIC DEVELOPER

Hermann Schultes, Mainz-Mombach, Germany, assignor to Deutsche Gold- und Silber-Scheideanstalt, vormals Roessler, Frankfort-on-the-Main, Germany, a company of Germany

No Drawing. Application January 10, 1936
Serial No. 58,541

3 Claims. (CL 95—88)

In my former United States Patent No. 2,017,295 I have shown that pyrogallol monoalkyl ethers or their homologues are very useful as photographic developers.

5 I have now discovered that photographic developers of excellent properties may be obtained by mixing the aforesaid pyrogallolic compounds with hydroquinone.

10 It is known that hydroquinone itself was formerly suggested for developer purposes. Nevertheless hydroquinone is objectionable in so far as it requires a relatively great amount of time to perform the development of latent photographs. After the course of this longer period of time 15 the development occurs too hardly. This fact on the other hand is very disadvantageous for the production of true photographs. Furthermore hydroquinone imparts to the photographs a faded yellowish colour.

20 On the other hand pyrogallol monoalkyl ether itself produces soft photographs within a relatively short period of time, an effect, which is often undesirable. It was suggested to use combinations consisting of hydroquinone and p-methyl- 25 amino-phenol as developers. These mixtures however, are objectionable as they have an aggressive and dyeing effect upon the skin. The developers according to the present invention are free from these disadvantages, in spite of the 30 fact that pyrogallol, itself produces a skin dyeing effect.

The present invention avoids the above mentioned disadvantages. When using hydroquinone in admixture with e. g. pyrogallol monomethyl 35 ether, a developer is obtained which enables the development of the photograph to be performed within an exceedingly short period of time. During this period of time the development proceeds gradually so as to obtain photos which are absolutely true to the original, without the production 40 of undesirable yellowish colours.

According to the present invention hydroquinone may be used in combination with any pyrogallol monoalkyl ether or homologues thereof. Mixtures of these pyrogallol compounds may likewise be used. Good results are obtained by using mixtures of hydroquinone with pyrogallol monomethyl ether or in an analogous manner pyrogallol monomethyl ether, and the like. By the 45 use of methyl pyrogallol monoalkyl ether, ethyl pyrogallol monoalkyl ether or generally spoken pyrogallol monoalkyl ethers substituted in the benzene nucleus, a further acceleration of the development effect is obtained.

50 The proportion of hydroquinone and pyrogallol compound according to the present invention may vary in a wide range. However, I prefer to use mixtures of e. g. pyrogallol monomethyl ether

and hydroquinone in the ratio of, say 1:1. Mixtures with a greater amount of hydroquinone (e. g. twice that of the weight of pyrogallol monomethyl ether) yield excellent results.

Other developers known per se e. g. p-methyl-amino-phenol may be admixed to the above described mixtures.

For the purpose of giving those versed in the art a better understanding of the invention, the following specific and illustrative examples are given:

Example 1

A photographic developer is prepared with about 100 parts by weight of water, 3.6 g. sodium sulfite ($Na_2SO_3 \cdot 7H_2O$), 3.6 g. potassium carbonate, 0.07 g. potassium bromide and 0.4 g. of a mixture consisting of equal parts by weight of hydroquinone and pyrogallol monomethyl ether.

This mixture may be advantageously used for developing positives. Hydroquinone and pyrogallol compound in the ratio of 1:2 are also suitable.

Example 2

The following developer which is suited for developing negatives consists of: 100 parts by weight of water, 7.2 g. sodium sulfite ($Na_2SO_3 \cdot 7H_2O$),

3.6 g. sodium carbonate, 0.07 g. sodium bromide and 0.6 g. of a mixture consisting of methyl pyrogallol monomethyl ether and hydroquinone in the proportion of 1:2.

Example 3

Instead of the above described mixtures of hydroquinone and pyrogallol compounds the following mixture may be likewise used: 1.5 parts by weight of pyrogallol monomethyl ether, 1.5 parts by weight of hydroquinone, 0.5 part by weight of p-methylamino-phenol sulfate (so called "Metol").

In spite of the fact that the above mentioned pyrogallolic compounds as well as hydroquinone are effective developers, it could not be foreseen that mixtures of both offer properties surpassing by far the efficiency of the components.

I claim:—

1. A photographic developer containing pyrogallol monoalkyl ether together with hydroquinone.

2. A photographic developer containing monomethyl ether of pyrogallol together with hydroquinone.

3. A photographic developer containing monomethyl ether of methyl pyrogallol together with hydroquinone.

HERMANN SCHULTES.
